(57) **CLAIM**

We claim the ornamental design for a face mask, as shown and described.

DESCRIPTION

FIG. 1 is a front, right perspective view of a face mask showing the new design in a condition of use shown worn by a model;

FIG. 2 is a rear, left perspective view thereof in a condition of use shown worn by a model;

FIG. 3 is a front elevation view of the face mask;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

In the drawings, the equal-length broken lines showing a mask and straps depict portions of the face mask that form no part of the claimed design. The equal-length broken lines in FIGS. 1 and 2 showing a human head depict environmental structure that forms no part of the claimed design. All broken lines form no part of the claimed design.
